CLAIM

I claim the ornamental design for a soap scooper, as shown and described.

DESCRIPTION

FIG. 1 is a perspective view of my new design for a shower soap scooper with an elongated plastic rod, a plastic hook at a top end of the rod and a plastic shovel at a bottom end of the rod;

FIG. 2 is a front view of the plastic shovel of the soap scooper with the plastic rod shown slanting away from the viewer;

FIG. 3 is a rear view of the plastic shovel of the soap scooper with the plastic rod slanting toward the viewer;

FIG. 4 is a left side view of the soap scooper;

FIG. 5 is a right side view of the soap scooper;

FIG. 6 is a top view of the plastic shovel of the soap scooper with the plastic rod shown slanting away from the viewer;

FIG. 7 is a bottom view of the soap scooper;

FIG. 8 is a rear view of the plastic hook at the top end of the rod; and,

FIG. 9 is a front view of the plastic hook at the top end of the rod.

The dash dot dash lines shown in the drawings represent broken away lines and center lines along the length of the soap scooper for clarity of illustration.

Structure that is not part of the claimed design is represented by broken lines.
